UNITED STATES PATENT OFFICE.

WILLIAM JOHNSTON READY, OF RICHMOND, VIRGINIA, ASSIGNOR TO AMERICAN
GLASS WORKS, INCORPORATED, OF RICHMOND, VIRGINIA, A CORPORATION.

DESIGN FOR A GLASS BOTTLE.

Application filed March 31, 1926. Serial No. 17,137. Term of patent 7 years.

To all whom it may concern:

Be it known that I, WILLIAM JOHNSTON READY, a citizen of the United States, residing at Richmond, in the county of Henrico and State of Virginia, have invented a new, original, and ornamental Design for a Glass Bottle, of which the following is a specification, reference being had to the accompanying drawing, forming a part thereof.

In the drawing:

Figure 1 is a front elevation of a glass bottle showing my new design;

Figure 2 is a side elevation thereof;

Figure 3 is a bottom plan view; and Figure 4 a top plan view.

I claim:

The ornamental design for a glass bottle, as shown.

WILLIAM JOHNSTON READY.
